UNITED STATES PATENT OFFICE

GORDON E. ROEDDING, OF GRAND RAPIDS, MICHIGAN, ASSIGNOR TO GRAND RAPIDS
BRASS COMPANY, OF GRAND RAPIDS, MICHIGAN, A CORPORATION OF MICHIGAN

HINGE

Application filed May 28, 1931. Serial No. 540,601.

The present invention relates to hinges; and its object is, generally, to provide a hinge improved in respects hereinafter appearing; and more particularly, to provide a hinge whose hinge members may be readily connected in swingable relation; and further, to provide a hinge having improved bearings; and further, to provide a hinge made partially of sheet metal bent to required shape; and further, to provide a hinge which may be very economically made and nevertheless be strong.

These objects are attained by, and the invention finds preferable embodiment in, the hinge particularly described in the body of this specification and illustrated by the accompanying drawing, in which:

Figure 1 is a front elevational view of a hinge connecting a door closure and a door jamb, fragments of which are shown;

Figure 2 is a bottom plan view of said hinge, the door closure and jamb being shown in section taken on line 2—2 of Figure 1;

Figure 3 is a bottom plan view of a portion of the hinge, other portions thereof being shown in section taken on the same line 2—2;

Figure 4 is a sectional view of the hinge taken on line 4—4 of Figure 1; and

Figure 5 is an inner side view of the hinge. In this drawing is illustrated a hinge, adapted for use on refrigerators and the like, comprising a hinge member 1 having a head portion 2 of globular form and a shank portion 4 adapted to be thrust into a bore 5 in the body of the refrigerator or the jamb 6 of its door opening and being internally threaded for receiving a mounting screw bolt 7. A pintle 8 is seated in a bore 9 in said head and its end portions 10 extend outwardly from

said head 2. The hinge comprises also the other hinge member 11 made of sheet metal and having a flat portion extending at 12 parallelly with the face of the door closure 13, then inclinedly inwardly at 14, and then parallelly with said face at 15 where it is mounted on the closure's inner side as by screws 16.

This second hinge member 11 also has spaced hollow extensions 17 embracing the head 2 between them and covering and concealing from view said end portions 10 of the

pintle. These hollow extensions 17 are shown conical in shape, their mutually adjacent edges 18 being the bases of such cones—turnably bearing on the opposite sides 3 of the globular head portion 2 of the hinge member 1.

Tongues 19 project from the ends of these extensions 17 and are bent under said end portions 10 of the pintle to connect the hinge members together in turnable relation. It will be seen that an economically constructed hinge is thus provided, in which the hinge members are readily connected, the pintle is concealed from view, an ornamental appearance is presented, and in which dirt-collecting parts are eliminated to a marked degree, thus assuring a sanitary fixture so desirable in refrigerators and food containers.

It will also be seen that the edges 18 of the conical extensions 17, bearing on the globular head portion 2 of hinge member 1 in a circular path around the pintle 8 and outwardly spaced therefrom, provides a braced construction whereby the hinge member 11 is held securely against tilting from the axis of the pintle, so that the connection of the hinge members 1 and 11 by the tongues 19 or the like need not be so strong as if said bearings of the edges 18 on the globular head 2 were absent.

The invention being intended to be pointed out in the claims, is not to be limited to or by details of construction of the particular embodiment thereof illustrated by the drawing or hereinbefore described.

I claim:

1. In a hinge: a hinge member having a globular head provided with a pintle whose end portions extend outwardly from its opposite sides, and a shank adapted to be inserted into a bore in a door jamb for mounting said member thereon; a second hinge member made of sheet metal having a flat portion adapted to be mounted on a door closure, and spaced hollow extensions embracing the head of the first-mentioned hinge member and covering the pintle's end portions, said extensions having tongues bent under said end portions respectively to connect the hinge members together turnably.

2. In a hinge: a hinge member having a globular head provided with a pintle whose end portions extend outwardly from its opposite sides; a second hinge member having spaced hollow tubular extensions embracing the globular head and covering the pintle's end portions, the mutually adjacent edges of the tubular extensions turnably bearing spacedly from the pintle on the opposite sides of the globular head, said extensions having other bearings inside the same receiving the ends of the pintle.

In testimony whereof I have hereunto set my hand at Grand Rapids, Michigan, this 15 25th day of May, 1931.

GORDON E. ROEDDING.
